CLAIM

The ornamental design for a combined food container and table mat, as shown and described.

DESCRIPTION

FIG. 1 is an isometric view from front/left side of an unconverted combined food container and table mat.

FIG. 2 is a front view of an unconverted combined food container and table mat.

FIG. 3 is a back view of an unconverted combined food container and table mat.

FIG. 4 is a left-side view of an unconverted combined food container and table mat.

FIG. 5 is a right-side view of an unconverted combined food container and table mat.

FIG. 6 is a top view of an unconverted combined food container and table mat.

FIG. 7 is a bottom view of an unconverted combined food container and table mat.

FIG. 8 is a flat pattern view of an unfolded combined food container and table mat illustrating perforations and fold lines shown for clarity of illustration; and,

FIG. 9 is an inverted isometric view of a converted combined food container and table mat from front/left side.

1 Claim, 8 Drawing Sheets
